UNITED STATES PATENT OFFICE.

HERMAN OSSWALD, OF NEW YORK, N. Y., ASSIGNOR TO THE V. & O. PRESS COMPANY, OF
GLENDALE, NEW YORK, A CORPORATION OF NEW YORK.

POWER-PRESS.

No. 880,239.

Specification of Letters Patent.

Patented Feb. 25, 1908.

Application filed June 22, 1905. Serial No. 266,381. Renewed August 23, 1907. Serial No. 389,872.

To all whom it may concern:

Be it known that I, HERMAN OSSWALD, a citizen of the United States, and resident of the borough of Brooklyn, in the city and 5 State of New York, have invented a new and useful Improvement in Power-Presses, of which the following is a specification.

My invention relates to a power press and more particularly to a press for cutting and 10 forming sheet metal and other material with the object in view of providing convenient means for controlling the action of the press.

The press to which my present invention applies is of the type shown, described and 15 claimed in Letters Patent No. 769,955 granted me September 13, 1904, and my present invention is directed particularly to means for preventing the locking of the shaft to the drive wheel for more than a single revolution 20 of the shaft in the event the operator should keep the operating treadle depressed longer than intended, while at the same time provision is made for operating the press continuously so long as the foot treadle is depressed 25 when for any reason it is desired to do so.

In the accompanying drawings, Figure 1 is a view of the press in side elevation partly in section, showing the parts in the position which they assume when the shaft is not 30 locked to the drive wheel, Fig. 2 is an enlarged view in detail partly in section and partly in elevation, showing the parts in the position which they assume when the latch for operating the switch plate is withdrawn, 35 and thrown out of engagement with the stop, Fig. 3 is an enlarged view in detail partly in section, taken in the plane of the line A—A of Fig. 1, showing in dotted lines the position which the latch operating cam may assume 40 when it is desired to operate the shaft continuously. Fig. 4 is an enlarged transverse section through the drive shaft, Fig. 5 is a partial section taken longitudinally through the shaft and hub of the drive wheel and 45 parts adjacent thereto, the section being taken in the plane of the line B—B of Fig. 4, Fig. 6 is a transverse section through the shaft in the plane of the line C—C of Fig. 5, Fig. 7 is a section through Fig. 6 in the plane 50 of the line D—D showing the locking dog in full length, and Fig. 8 is a transverse section through the shaft in the plane of the line E—E of Fig. 5.

The pedestal is denoted by 1, the superposed rocking frame which carries the operating shaft is denoted by 2, the operating shaft by 3 and the drive wheel loosely mounted on the shaft 3, is denoted by 4.

The switch plate which slides toward and away from the shaft 3, is denoted by 5, the frame in which it slides is denoted by 6 and the dog which slides to a limited extent parallel with the axis of the shaft 3 and serves to lock the wheel 4 to the shaft 3, is denoted by 7.

The shaft 3 has an enlarged portion 26 in which there is formed a groove 27 for receiving an annular ring 28. The ring 28 has an inwardly projecting wedge-shaped portion 29, (see Fig. 7) which coacts with a recess 30 in the dog to withdraw the dog from locking engagement with the hub of the wheel 4 or to permit the dog to slide into locking engagement with the hub of the wheel 4 under the tension of the dog actuating spring 31 according as the ring 28 is rocked in the one direction or the other in the groove 27. The ring 28 co-operates with the switch plate 5 to operate the dog 7.

The parts above enumerated operate in substantially the same manner as that shown and described at length in my Letters Patent above referred to and the structure of the parts is quite similar to that shown in said patent with the following exception, to wit: The switch plate 5 is provided with two stems denoted by 8 and 9 respectively and these stems are each provided with a spring coiled thereon, the springs being denoted by 10 and 11, for the purpose of holding the switch plate 5 normally in its advanced position with respect to the shaft 3, that is, in position to crowd the locking dog 7 out of its position for locking the drive wheel 4 to the shaft.

In practice it frequently becomes desirable to rotate the shaft 3 a single revolution and then pause before again rotating it. At the same time unless some provision is made for automatically arresting the rotation of the shaft when a single revolution is completed, the operator is liable to hold the foot treadle 12 depressed too long and the shaft starts on a second revolution or if the operator have his mind closely on the operating of the treadle 12, it detracts from his efficiency in pay-

ing close attention to the adjustment of the work which the press is operating on.

To leave the operator free so far as devoting close attention to the treadle is concerned 5 and to stop the press after the shaft has made a single revolution when the work is of a character to require such stopping, I provide the following mechanism. On the face of the switch plate 5, I locate a stop 13 and to 10 the rocking arm 14, with which the operating rod 15 leading to the foot treadle 12 connects, I pivot a latch 16, the bite 17 of which is fitted to receive the end of the stop 13 and thereby give the latch a good operating hold 15 of the switch plate 5 for the purpose of drawing the switch plate back and permitting the dog 7 to lock the drive wheel to the shaft whenever the treadle 12 is depressed. I further provide the latch 16 with an inclined 20 surface 18 which contacts with an inclined face 19 on a latch operating cam 20 when the latter is swung up into operative position as shown in Figs. 1 and 2. The cam 20 is hinged at 21 to the frame which supports the 25 switch plate so that when not required for use it may be swung down out of operative position as shown in dotted lines in Fig. 3. The latch 16 is pressed toward the stop 13 and toward the cam 20 by means of a spring- 30 actuated presser pin 22, the stem 23 of which passes longitudinally through a socket piece 24 screwed into the frame 6, and the said stem is surrounded within the socket piece 24 by a coil spring 25 to press the pin 22 toward 35 the latch.

In operation, when it is desired to limit the rotary movement of the operating shaft to a single rotation before a pause, the latch operating cam 20 is thrown up into operative position as shown in Figs. 1 and 2, and when the treadle 12 is depressed to draw the switch plate back and permit the dog 7 to lock the wheel to the shaft, the initial movement of the latch will draw the switch plate back and 45 start the operation of the shaft while its further movement because of the engagement of the incline 18 on the latch with the incline 19 on the cam will throw the latch up out of engagement with the stop 13 and the switch 50 plate will thereupon spring back under the influence of its operating springs 10 and 11, into position to withdraw the dog 7 and stop the rotation of the shaft just as soon as it has completed a revolution. On the other hand, 55 when it is desired to leave the latch 16 at all times in connection with the stop 13, the cam 20 may be turned down out of operative position as shown in dotted lines, Fig. 3, and when so thrown out of position, the shaft will 60 remain locked to the drive wheel just so long as the treadle 12 is depressed, whether for few or many revolutions.

What I claim as my invention is:

1. The combination with the shaft and its drive wheel, of means for locking the shaft to and releasing it from the drive wheel, means for operating said locking and releasing means and controlling means for making said operating means automatic or not, at pleasure. 70

2. The combination with the shaft, the drive wheel, the dog, for locking the shaft to the drive wheel and the switch plate for operating the dog, of a latch for operating the switch plate and means for throwing the latch out of engagement with the switch plate after the switch plate has moved a pre-determined distance. 75

3. The combination with the shaft, the drive wheel, the dog for locking the shaft to the drive wheel and the switch plate for operating the dog, of a latch for operating the switch plate and a cam for throwing the latch out of engagement with the switch plate intermediate of the limits of its stroke. 80

4. The combination with the shaft, the drive wheel, the dog for locking the shaft to the drive wheel and the switch plate for operating the dog, of a latch for operating the switch plate and a movable cam for throwing the latch out of engagement with the switch plate intermediate of the limits of its stroke. 90

5. The combination with the shaft, the drive wheel, the dog for locking the shaft to the drive wheel and the switch plate for operating the dog, of a latch for operating the switch plate and a hinged cam for throwing the latch out of engagement with the switch plate intermediate of the limits of its stroke. 100

6. The combination with the shaft, the drive wheel, the dog for locking the drive wheel to the shaft and the switch plate for operating the dog, of a rocking arm, a latch pivoted to the rocking arm in position to engage and disengage the switch plate and a foot treadle connected with the rocking arm for operating the latch and hence the switch plate. 105

7. The combination with the shaft, the drive wheel, the dog for locking the shaft to the drive wheel and the switch plate for operating the dog, of a spring-actuated latch for engaging the switch plate and a treadle for operating the latch. 115

In testimony, that I claim the foregoing as my invention, I have signed my name in presence of two witnesses, this 19th day of June, 1905.

HERMAN OSSWALD.
